COVER FOR A WARM AIR FURNACE REGISTER

Harriet L. Postlewait, Champaign, Ill.

Application January 22, 1940, Serial No. 315,069

1 Claim. (Cl. 98—114)

This invention relates to a cover for a warm air furnace register and has for an object to provide a cover of this type which may be easily applied and removed from the register without the use of tools and which will prevent dust escaping from the warm air shaft or collecting in the register itself.

A further object is to provide a device of this character which will be formed of a few strong simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming a part of this specification:

Figure 1 is a longitudinal sectional view of a cover constructed in accordance with the invention, applied to a register.

Figure 2 is a perspective view of the cover.

Figure 3 is an enlarged detail sectional view of the cover taken on the line 3—3 of Figure 2.

Referring now to the drawing in which like characters of reference designate similar parts in the various views, 10 designates a conventional hot air register having a peripheral flange 11 exposed on the inner surface of a wall 12 and secured to the wall by screws 13 or other fasteners.

In carrying out the invention, the cover 14 is formed of a single blank of heavy cardboard,

preferably of the type from which chair seats are manufactured, the length and breadth of the blank being sufficient to extend over the exposed surface of the peripheral flange 11 of the register and to seal the register dustproof. For securing the cover in place a pair of upper and lower jaws 15 and 16 formed of channel pliable metal, each have one leg 17 secured in a slot 18 formed in the respective edge of the cover 14. The other leg 19 overlaps and is spaced from the inner surface of the cover. Staples 20 are passed through the cover and through the leg 17 of the jaw and clinched over the inner surface of the cover, as best shown in Figure 3.

To apply the cover it is simply necessary to hook the free leg 19 of each jaw over the edge of the flange 11 of the register, as best shown in Figure 1, and since the leg is of sufficient length to terminate short of the screws 13, no special tools need be used.

From the above description it is thought that the construction and operation of the invention will be fully understood without further explanation.

What is claimed is:

A cover for furnace registers having a peripheral flange comprising, a blank of cardboard adapted to overlap the front face of the peripheral flange, jaws formed of channel pliable metal, each having one leg imbedded in the edge portion of the blank, and staples clinched through said leg and through the blank, the other leg of each jaw being adapted to be hooked over the peripheral flange and extend along the rear face thereof.
